UNITED STATES PATENT OFFICE.

MASON A. BAMBOROUGH AND HAROLD A. BAMBOROUGH, OF CHICAGO, ILLINOIS,
ASSIGNORS TO LELA L. BAMBOROUGH, OF BEAVER, PENNSYLVANIA.

DESIGN FOR AN ELECTRIC-LIGHT GLOBE.

Application filed June 14, 1923. Serial No. 6,493. Term of patent 7 years.

To all whom it may concern:

Be it known that we, MASON A. BAMBOROUGH and HAROLD A. BAMBOROUGH, both citizens of the United States, and both residing at Chicago, in the county of Cook and State of Illinois, have invented a new, original, and ornamental Design for Electric-Light Globes, of which the following is a specification, reference being had to the accompanying drawing, forming part thereof.

In the drawing Fig. 1 is a perspective

view, looking upwards, showing my new design applied to an electric light globe; Fig. 2 is a perspective view, looking downwards, showing the design; Fig. 3 is a side elevation thereof and Fig. 4 is an end view looking from below.

We claim:

The ornamental design for an electric light globe, as shown.

MASON A. BAMBOROUGH.
